ATTORNEY.

UNITED STATES PATENT OFFICE.

JAMES H. COLLINS, OF HARRISBURG, PENNSYLVANIA.

SPARK-PLUG.

1,358,292.

Specification of Letters Patent.

Patented Nov. 9, 1920.

Application filed March 8, 1919. Serial No. 281,345.

To all whom it may concern:

Be it known that I, JAMES H. COLLINS, a citizen of the United States, residing at Harrisburg, in the county of Dauphin and State of Pennsylvania, have invented certain new and useful Improvements in Spark-Plugs, of which the following is a specification.

The object of this invention is to provide a spark-plug of improved design for internal combustion engines, and adapted to overcome the defects commonly experienced in other plugs, and resultingly recognized by increased efficiency therover.

After exhaustive study upon the subject of spark-plug construction and performance, certain unfailing rules have been observed regarding their general characteristics. With a given supply of electric current, and the same spark-gap is used, the spark of a plug having a single gap between a pair of electrodes is "fatter," or of more intense heat than where a plurality of gaps is used.

But with a single gap, it is obvious that, as a result of anything less than a complete combustion of the gases, a deposit occurs and tends eventually to bridge said gap, whereas, other factors being equal, the same deposit will generally take much longer to short circuit a multiplicity, care being exercised not to increase the number of the same unreasonably, and thereby develop an infinite number of sparks but with greatly decreased ability to ignite the usual gaseous mixture.

These are by no means the only rules which must be recognized as governing the details of spark-plug construction, but they will suffice for purposes of illustrating the care which must be exercised in designing any new departure in this class of devices. And as a result of taking them collectively, the construction hereinafter described in detail has been developed, and the same has been proved to insure dependable operation under the most exacting conditions presented by commercial service.

Thus, an object of the invention is to provide a spark-plug adapted to produce hot "fat" sparks simultaneously across a plurality of spark-gaps; to provide means for adjusting the distances across all of said gaps simultaneously; to provide a positive electrode so constructed as to disrupt the spark discharges therefrom in order to cause them to penetrate and ignite the gaseous

mixtures in a cylinder with greater certainty; to provide a construction operative to permit the porcelain part or parts of the improved spark-plug to yield, as may be desired, to the explosions within a cylinder, instead of being rigidly held in position and thereby subjected to fracturing stresses; and to provide with all acme of simplicity in the construction of the improved spark-plug its various details.

With these and other objects in view, the invention consists in novel details both in construction and operation, hereinafter fully brought out in the following description, when read in conjunction with the accompanying drawings, in which figure 1 is an elevation of the preferred embodiment of the invention; Fig. 2 is a vertical diametrical section of the same; Fig. 3 is a bottom plan view of the same; Fig. 4 is a section on the line 4-4 of Fig. 2; and Fig. 5 is an enlarged detail diametrical section of the central electrode-head.

Referring to the drawings, a metal cylinder 1 is provided, upon one end with external screw-threads 2, while its outer end portion 3 is provided externally with screw-threads adapted to engage corresponding threads within an aperture in the cylinder 85 of an internal combustion engine (not shown), while connecting the main and reduced portions of said metal cylinder is a plain wall surface 4, functioning as hereinafter described.

Within the larger portion of the cylinder 1 and immediately adjacent to the surface 4 is an annular gasket 5, preferably made of non-inflammable fibrous material such as asbestos, and upon which in turn is placed an annular gasket 6 of relatively soft material such as copper. The porcelain member 7, of substantially the same diameter as the member 1, is inserted thereinto and with a reduced end portion 8 extending into the reduced portion 3 of said member, while the said porcelain is provided through its enlarged portion with a centrally positioned bore 9, terminating in a larger similarly positioned bore 10 passing through its reduced portion.

Extending through the bore 9 in the porcelain member 6 is a threaded stem 11 carrying a nut 12, which, co-operating with the sides of bore 10, revolves with respect to the said stem upon turning the latter, and thus operates to shift said stem longitudinally

- through the said bores. The inner end portion of the said stem (considering a spark-plug as when positioned operatively with respect to an engine cylinder) comprises one 5 of the electrodes separated by a gap, between which sparks jump for the purpose of igniting the explosive gases within the cylinder of an internal combustion engine in the usual manner.
- 10 Surrounding the stem 11, and abutting against the larger end of the porcelain member 7, is a loosely mounted washer 13, against which is pressed a radially outwardly flanged portion 14 of a non-inflammable cylinder 15, closely yet slidably surrounding the stem and in turn surrounded by a cylindrical portion 16 of a second non-inflammable member provided with a radially outwardly extending annular flange 17, oppositely positioned with respect to the flange 14, and between which flanges extends a compression coil-spring 18 surrounding the telescoping portions 14 and 16 of the respective non-inflammable members.
- 15 The major portion of the spring and co-operating members thus described are positioned within the enlarged portion 19 of a bore 20, extending respectively through an enlarged section 21 and a reduced section 22 of a second porcelain member, said sections of this member being connected by a radially extending external surface 23 forming an annular shoulder against which bears uniformly an annular washer 24 of relatively 25 soft material such as copper. With the inner parts of the device constructed and positioned as thus described, an internally threaded cap 25, provided with a central bore 26, is then slipped over the second portion 30 of a second porcelain member and screwed firmly upon the threaded portion 2 of the metal cylinder 1.
- Upon the opposite or outer free end of the stem 11 is positioned a lock-nut 27, while adjacent thereto said stem is provided with a knurled binding-nut 28, for the purpose of removably yet firmly attaching to said stem the usual electric conductor. In order to 35 adjust the longitudinal position of the stem 50 forming a part of this improved spark-plug, the binding-nut being loose, the lock-nut 27 is loosened, and said stem revolved in the direction desired for the purpose of shifting its electrode section into operative position 55 with respect to the reduced portion 3 of the member 1, which reduced portion forms a second electrode, or out of this position it is free from said reduced portion for the purpose of cleaning both electrodes.
- 60 The central electrode, which is the inner end portion of the stem 11, is made in such manner as to comprise two spaced disks 29 and 30, integral with said stem and forming at first radially extending flanges lying in 5 parallel planes. However, these spaced
- disks are scalloped at spaced intervals 31 in order to form between adjacent scallops blunt discharge points 32.
- The oppositely disposed points of each pair are then brought toward each other as 70 clearly shown in Fig. 5, so that the pointed sections, together with that part of the stem 11 connecting them, co-operate to form in cross-section a horse-shoe shape, after which the extremities of said points are turned off 75 concentrically with said stem, so that the outer surfaces of the points of each pair are in alinement with each other, and thereby at all times equi-distant from the adjacent portion of the electrode section of the member 1, as well as insuring the distances being 80 equal between each pair of said points and said portion of the second electrode.
- In setting the position of the central electrode longitudinally with respect to the second or surrounding electrode, care is taken to so adjust the former as to insure the plane of the peripheral surface extremity of the second electrode passing centrally between the points of each of the pairs of points upon 85 said central electrode, because of the fact that electric sparks universally tend to jump from and toward the sharpest edges or points of neighboring members of opposite polarity. Thus, while the discharge points of 90 the disk 29 are actually within the reduced electrode portion of the member 1, sparks jump from said points to the inner edge of the surrounding electrode, toward which edge sparks also jump from the pointed lateral extremities of the disk 30, forming thereby a continuous spark discharge from the points of each pair to the neighboring portion of a second electrode, and additionally, while the actual theory of the discharge 95 may not be fully understood at this time, it is believed that the peculiar character of the discharge is at least partially due to the discharges from the disk 29 to the nearest edge of the electrode 3 being disrupted or repelled to a certain extent by the charge of the same polarity upon the neighboring points of the disk 30. Similarly, it 100 appears that a discharge from the points of the disk 30 is arced outwardly and possesses an increased fiery characteristic, because of the nearness of the respective oppositely positioned points of the disk 29 of the same 105 polarity.
- 110 Thus, this construction effects a discharge 115 from the central to the surrounding electrode of a considerably different character, the central electrode having the form of a continuous disk, a gear-shaped disk provided with sawteeth, or a central electrode comprising one or more discharge points extending radially therefrom, such as occurs in many well-known types of devices of this character.
- Having thus described my invention, 120

what I claim and desire to protect by Letters Patent of the United States is:—

1. A spark-plug, comprising a casing, a porcelain seated within said casing, a second porcelain within and normally seated against said casing, an electrode extending through said porcelains and normally fixed with respect to said first portion, and resilient means between said porcelains, operative to permit said second porcelain to yield in accordance with explosions within a cylinder of an internal combustion engine, and to move with respect to said electrode.
2. A spark-plug, comprising a metal casting forming one electrode, a porcelain seal seated within said casing, a second porcelain within said casing, a second electrode supported by said porcelain, and resilient means between said porcelains, operative to permit said second porcelain to yield in accordance with explosions within a cylinder of an internal combustion engine and independently of said second electrode.
3. A spark-plug, comprising an electrode having a pair of concentric disks, the peripheral portions of said disks being separated a less distance than their central portions.
4. A spark-plug, comprising an electrode having a pair of concentric disks slightly scalloped to provide circumferentially spaced radially extending projections correspondingly positioned upon each of said disks, and the extremities of said projections of each pair being closer together than the central portions of said disks.
5. A spark-plug, comprising a metal casting having an annular edge portion forming one electrode, and a second electrode comprising two spaced disks uniformly and respectively spaced away from the edge portion of said first electrode.
6. A spark-plug, comprising a metal casting having an annular edge portion forming one electrode, and a second electrode positioned centrally within said first electrode, and comprising spaced disks having spaced peripheral projecting portions spaced an equal distance from the edge portion of said first electrode and the corresponding projection.
7. In a spark-plug, an electrode comprising a stem provided with spaced flanges, each of said flanges scalloped at intervals to provide intermediate substantially radial projections oppositely disposed upon said flanges.
8. In a spark-plug, an electrode comprising a stem provided with spaced flanges,
- each of said flanges scalloped at intervals to provide intermediate substantially radial projections oppositely disposed upon said flanges, the projections upon each of said flanges being directed toward the corresponding projections upon the other of said flanges.
9. In a spark-plug, an electrode comprising a stem provided with spaced flanges, each of said flanges scalloped at intervals to provide intermediate substantially radial projections oppositely disposed upon said flanges, the projections upon each of said flanges being directed toward the corresponding projections upon the other of said flanges, and the radially outer surfaces of said projections being in alinement and concentric with said stem.
10. In a spark-plug, an electrode comprising a stem provided with spaced flanges, each of said flanges scalloped at intervals to provide intermediate substantially radial projections oppositely disposed upon said flanges, and a surrounding electrode surface positioned so that the plane of said surface is substantially perpendicular to the axis of said stem and intersects said stem substantially midway between said flanges.
11. In a spark-plug, an electrode comprising a stem provided with spaced flanges, each of said flanges scalloped at intervals to provide intermediate substantially radial projections oppositely disposed upon said flanges, the projections upon each of said flanges being directed toward the corresponding projections upon the other of said flanges, and a surrounding electrode surface positioned so that the plane of said surface is substantially perpendicular to the axis of said stem and intersects said stem substantially mid-way between said flanges.
12. In a spark-plug, an electrode comprising a stem provided with spaced flanges, each of said flanges scalloped at intervals to provide intermediate substantially radial projections oppositely disposed upon said flanges, the projections upon each of said flanges being directed toward the corresponding projections upon the other of said flanges, the radially outer surfaces of said projections being in alinement and concentric with said stem, and a surrounding electrode surface positioned so that the plane of said surface is substantially perpendicular to the axis of said stem and intersects said stem substantially mid-way between said flanges.

In testimony whereof I have affixed my signature.

JAMES H. COLLINS.
